CRATE FOR MILK CONTAINERS OR THE LIKE

Houston Rehrig, Los Angeles, Calif., assignor to Rehrig Pacific Company, Los Angeles, Calif., a corporation of California

Filed Dec. 27, 1967, Ser. No. 9,946

Term of patent 14 years

Int. Cl. D9—04

U.S. Cl. D9—177

FIG. 1

FIG. 2

FIGURE 1 is a front perspective view of a crate for milk containers or the like showing my new design; and

FIGURE 2 is a side elevation thereof on an enlarged scale, the other sides being identical thereto and the bottom being of a conventional configuration.

The dominant features of the design reside in the full line portions of the drawing.

I claim:

The ornamental design for a crate for milk containers or the like, substantially as shown and described.
